METHOD FOR THE PREPARATION OF
PERFLUOROOLEFINS

Richard Ensign Brooks, Wilmington, Del., assignor to
E. I. du Pont de Nemours and Company, Wilmington,
Del., a corporation of Delaware

No Drawing. Application May 12, 1958
Serial No. 734,439

7 Claims. (Cl. 260—653.3)

The present invention relates to a method for the preparation of perfluoroolefins, and more particularly to a method for the preparation of perfluoroolefins by pyrolysis of perfluorocarbon acids.

It was heretofore known, U.S. Patent 2,601,536, issued June 24, 1952 to James D. LaZerte, and U.S. Patent 2,668,864, issued February 9, 1954 to Lyle J. Hals, Thomas S. Reid and George H. Smith, that alkali metal salts of perfluorocarboxylic acids herein also referred to as perfluorocarbon acids, could be decarboxylated and defluorinated to form perfluoroolefins. It is stated in these patents that the alkali metal salts are unique in their behavior when heated to temperatures at which this reaction occurs. Other perfluorocarboxylic acid derivatives and the acid itself are said not to decarboxylate or to only slightly decarboxylate to form the perfluoroolefins.

It is an object of the present invention to prepare perfluoroolefins by pyrolysis of aliphatic perfluorocarboxylic acids. It is another object of the present invention to prepare perfluoroolefins in high yields from perfluorocarboxylic acids.

The objects of the present invention are accomplished by a process which comprises passing a substantially anhydrous mixture of a perfluorocarboxylic acid having the formula $F-C_nF_{2n}-COOH$, where n is an integer from 2 to 11 and an inert gaseous diluent through a reaction zone maintained at a temperature of 400° C. to 650° C. and recovering a perfluorinated olefin having the formula $F-C_{n-2}F_{2(n-2)}CF=CF_2$.

In accordance with the present invention it was discovered, contrary to the disclosures of the prior art, that perfluoroolefins could be obtained in high yields by the decarboxylation of perfluorocarbon acids. It was found, however, that the decarboxylation occurred in significant and commercially attractive yields only if the perfluorocarbon acid was decarboxylated in vaporized form in the presence of an excess of gaseous diluent, preferably at hot zone contact times not exceeding five seconds. Diluents suitable in the process of the present invention are nitrogen, carbon dioxide and similar inert gases. The gaseous diluents are preferably employed in large excess, particularly suitable mixtures of diluent and vaporized acid are mixtures which contain less than 10% by volume the vaporized acid.

The decarboxylation may be carried out by various means. In the preferred method the mixture of acid and diluent is passed through a reaction tube heated to the desired reaction temperature. The resulting reaction products are condensed in cold traps and the perfluoroolefin is recovered and separated by means of distillation. The reaction tube may be made of stainless steel, or steel lined with silver, platinum or any other corrosion resistant metal. If desired, the tube may be filled with refractory oxides or other inert materials to achieve better heat transfer to the reaction mixture. The decarboxylation is generally carried out at atmospheric pressure, although higher or lower pressures may be employed, except the pressure may not exceed the critical pressure of

2

the acid at reaction temperatures in order to avoid condensation of the acid.

The invention is further illustrated by the following examples.

5

Example I
Into a "Monel" tube, 22.2 cm. long and having a 1.59 cm. inside diameter, heated to a temperature of 650° C., was passed a mixture of 3.5 ml./min. of vaporized perfluoropropionic acid and 500 ml./min. of carbon dioxide.

10 The contact time of the gases in the heated "Monel" tube was 3 seconds. The hot reaction gases obtained were condensed in a liquid nitrogen cold trap. Mass spectrographic analysis of the fluorocarbon products shows that 83% was tetrafluoroethylene. The example 15 was repeated without the use of a diluent. Only traces of tetrafluoroethylene were found in the reaction product.

Example II

Following the procedure of Example I, perfluorobutyric acid was charged to the heated "Monel" tube at the rate of 2 ml. per minute and mixed with carbon dioxide at the rate of 500 ml./min. Analysis of the resulting fluorocarbon products showed an 86% yield of perfluoropropylene.

25

Example III
Into a borosilicate glass tube, having a length of 12 in. and an inside diameter of 0.7 in., and containing in the center a plug of glass wool, heated to a temperature of 620° C., there was charged 3.4 g. of perfluoroctanoic acid over a period of 12 min. in a stream of nitrogen passed through the tube at the rate of 500 ml./min. The resulting reaction products were condensed in liquid nitrogen traps. There was obtained on distillation of the products 1.8 g. of perfluoroheptene-1 corresponding to a yield of 85% based on unreacted acid recovered. The example was repeated using carbon dioxide as the diluent. There was obtained 1.2 g. of perfluoroheptene-1 corresponding to a yield of 89% on the basis of unreacted acid recovered.

40 The above examples are not to be construed as limiting the process of the present invention, and various modifications will occur to those skilled in the art. The process, for example, is not limited by the structure of the perfluorocarbon acid employed. It is thus possible to prepare branched as well as linear perfluoroolefins from the corresponding perfluorocarboxylic acids. The process of the present invention is furthermore not limited to the number of carbon atoms in the perfluorocarboxylic acid. However, it is preferred to apply the process of the present invention to perfluorocarboxylic acids having less than 12 carbon atoms, since the chemical stability of perfluorocarboxylic acids having more than 12 carbon atoms is lower and results in a larger amount of decomposition of the acid and hence a lower yield. The process of the present invention is also suitable for the decarboxylation of dicarboxylic perfluorocarbon acids. In addition to the perfluorocarboxylic acids illustrated in the examples, there may be employed in the process of the present invention, perfluorocarboxylic acids such as perfluorisobutyric acid, perfluoropentanoic acid, perfluorosebacic acid, perfluorohexanoic acid, perfluoroheptanoic acid and perfluorodecanoic acid. In addition to the completely fluorinated acids employed in the decarboxylation of the present invention there may be employed 55 omega-hydroperfluorocarboxylic acids, which are essentially identical in their physical and chemical properties to the perfluorocarboxylic acids. Examples of such acids are 4-hydrohexafluorobutanoic acid, 7-hydrododecafluorohexanoic acid, etc.

60 The perfluoroolefins prepared by the process of the present invention are highly useful monomers which can

be employed in the formation of perfluorinated polymers having outstanding physical and chemical properties; particularly useful polymers prepared from the monomers of the present invention are polytetrafluoroethylene and copolymers of tetrafluoroethylene with perfluorinated monomers such as perfluoropropylene, perfluorobutene, perfluoropentene, etc.

I claim:

1. A process for the preparation of perfluoroolefins which comprises passing through a hot zone maintained at a temperature of 400 to 650° C. a perfluorocarboxylic acid having the formula $F-C_nF_{2n}COOH$ where n is an integer of 2 to 11 in an inert gaseous diluent, said perfluorocarboxylic acid being employed in a concentration of not greater than 10 volume percent of said diluent, and recovering a perfluoroolefin having the formula

15

5

2. The process as set forth in claim 1 wherein the perfluorocarboxylic acid is maintained in the hot zone for a contact time of less than 5 seconds.
3. The process as set forth in claim 2 wherein the perfluorocarboxylic acid is perfluoropropionic acid.
4. The process as set forth in claim 2 wherein the perfluorocarboxylic acid is perfluorobutyric acid.
5. The process as set forth in claim 2 wherein the perfluorocarboxylic acid is perfluoroctanoic acid.
6. The process as set forth in claim 2 wherein the diluent is nitrogen.
7. The process as set forth in claim 2 wherein the diluent is carbon dioxide.
